INVENTOR

John C. R. March.

By
Robert M. Barr.
ATTORNEY

UNITED STATES PATENT OFFICE.

JOHN C. R. MARCH, OF PHILADELPHIA, PENNSYLVANIA.

FAN ATTACHMENT FOR ROCKING CHAIRS.

Application filed September 12, 1922. Serial No. 587,685.

To all whom it may concern:

Be it known that I, JOHN C. R. MARCH, formerly a subject of the Emperor of Germany, having declared my intention to become a citizen of the United States, a resident of Philadelphia, county of Philadelphia, State of Pennsylvania, have invented certain new and useful Improvements in Fan Attachments for Rocking Chairs, of which the following is a specification.

Some of the objects of the present invention are to provide a fan actuated by the rocking motion of a chair or any other rocking device in a manner to simulate the manual manipulation of a fan; to provide means for imparting an oscillatory motion to a fan which can be readily applied to or removed from a rocking chair; to provide a fan operated by a rocking chair whereby currents of air are directed towards the occupant of the chair; to provide a rocker operated fan wherein the fan automatically changes its position at the end of each rocking movement; to provide means for actuating a fan by the movement of a rocking chair whereby the rocking effort is reduced to a minimum; and to provide other improvements as will hereinafter appear.

In the accompanying drawings, Fig. 1 represents a side elevation of a rocking chair equipped with one form of fan mechanism embodying the present invention; Fig. 2 represents a detail in section of the main bearing construction; Fig. 3 represents a detail in sectional elevation of the fan supporting mechanism; Fig. 4 represents a section on line 4—4 of Fig. 3; Fig. 5 represents a section on line 5—5 of Fig. 3; Fig. 6 represents a detail in elevation of one of the attaching brackets; Fig. 7 represents a plan of the same; Fig. 8 represents a plan of a brace arm; Fig. 9 represents a side elevation of a second attaching bracket; Fig. 10 represents a plan of the same; and Fig. 11 represents a detail in plan of a rod holder to cooperate with the brace arm.

Referring to the drawings, one form of the present invention is shown as removably secured to the back of a rocking chair 10 such as a porch rocker, and comprises a fan 11 of the palm leaf type, though any other kind of fan can be employed, which is arranged to be suspended from a laterally disposed hanger 12 supported by a rod 13

the lower end of which is adjustably held by a bracket 14 fixed to a suitable cross piece or other part of the back of the rocker 10.

For the purpose of supporting the hanger 12 for oscillating movements, to thus cause the fan to function, it is preferably formed as a sleeve, one end of which receives a spindle 15 and is made fast thereto by a bushing 16 and a thumb-screw 17. The spindle 15 passes axially through a bearing block 18 and has bearings in suitable bushings 20 which are preferably of the oil-less bearing type. The bearing block 18 has a threaded lug 21 to receive the upper end of the support rod, the arrangement of the parts being such as to position the hanger laterally over the seat portion of the chair so that the fan 11 is located to effectively produce currents of air towards any one sitting in the chair 10. The projecting end of the spindle 15 has a sheave or pulley 22 keyed or otherwise fixed thereon to transmit motion thereto.

In order to removably and adjustably support the fan 11 from the hanger 12, a suitable casting or body 23 is provided having a jaw member 24, the gripping face of which is partly spherical to conform to the contour of a ball part 25 fixed to the end of the hanger 12. A cooperating jaw member 26 is likewise provided with a partly spherical gripping face to engage the ball part 25, and is secured to the body 23 by a screw 27 having a coil spring 28 interposed between its head and the member 26. This construction is in effect a universal joint which permits the body 23 to be freely moved relatively to the ball part 25 but is held firmly by the spring 28 in any adjusted position. A fan clamp, in the form of a strip 30 having a corrugated face 31, has a cylindrical stem 32 snugly but rotatably fitting a hole 33 in the body 23 and is threaded to receive a nut 34 to hold the part in position. Springs 35 or other elastic medium are arranged to be slipped over the strip 30 with sufficient tension to bind the fan handle 26 to the strip 30 for purposes of operating.

As a means for automatically causing the fan 11 to direct a current of air towards the occupant of the chair 11, in either of its swinging movements, the strip 30 is preferably offset by a radial extension 37 from the stem 32, and a spring 38 extends

between the extension 37 and the hanger 12, the function of which is to limit the axial turning of the fan when the direction of its movement is changed. This construction causes the fan to assume a slightly angular position, irrespective of its direction of movement, which directs the air towards the occupant of the chair.

For transmitting rocking motion to the 10 sheave or pulley 22, a rope 40, or other belt drive, is wound about the sheave 22 and has one end fastened to an end of a coil spring 41, and its other end terminating in a hook 42. The other end of the spring 41 preferably has a hook 43 arranged to engage a thumb-screw 44 which serves to fix the lower end of the rod 13 in a tubular head 45 pivoted at 46 to the bracket 14. A ring 47 and thumb-screw 48 are carried by the 20 rod 13 to give the proper adjusted position of the rod 13 for the fan's location. The hook 42 is arranged to be secured to an eye 50 pivoted to a foot post 51, the lower end of which terminates in a cushioning cap 52 of suitable material to rest upon the 25 floor or other base support.

For the purpose of preventing the post 51 from leaving the floor under rocking motion, and also to hold the rope 40 taut during the forward rocking of the chair 10, a bushing 53 is mounted in the post 51, being adjustably held by a thumb-screw 54, and having laterally extending bearing pins 55 which are arranged to seat respectively in 30 the bifurcated ends 56 of a yoke 57 and be held against displacement by cotter pins 58 or the like. The yoke 57 forms the free 35 end of an arm 60 which is pivotally connected to a bracket 61. This connection consists of trunnions 62 seating respectively in bearing slots 63, so that while the arm 60 is free to have a certain amount of swing, it can also be quickly disconnected from the bracket 61. This bracket 61 is arranged 40 to be made fast to a suitable part of the lower portion of the rocker 10, and has a downwardly extending rod 64 preferably of tubular form, which is fixed by a wire 65 or the like to one of the chair rounds. 45 A spring 66 is arranged to be secured between the end of the rod 64 and a suitable one of the holes 67 of the arm 60 in order to place the desired amount of tension on the parts to prevent the rope 40 and post 51 50 from following the rocking motion of the chair. It will therefore be evident that the parts 62 and 63 have a horizontal pivot which allows the arm 60 to swing up or down while the part 61 also has a pivot 55 about a vertical axis of the post 64, and in this way the arm 60 is connected by a 60 form of universal joint so that the chair is free to be moved to one side or the other, or forward or backward, without disturbing the operation of the foot post 51. In

other words, the rocking chair can be moved within certain limits and the only effect upon the foot post 51 will be to swing it in the direction of movement where it will still perform its function of holding the 70 rope 40 so that the fan will operate as usual.

From the foregoing it will be apparent that the brackets 14 and 61 are the only parts which become permanently attached to the chair 10, and all of the fan operating parts are removable and may be quickly attached for fanning purposes whenever desired. With extra brackets provided, one fan unit may be moved from one chair to another, the arrangement being particularly advantageous when indoor rockers and porch rockers are both equipped with brackets.

With the device assembled upon a chair, the fan is caused to oscillate by a rocking motion imparted to the chair. Thus a forward rocking causes the spring 66 to be placed under tension so that as the pulley 22 describes a forward arc it will be rotated in one direction, thereby rocking the hanger 12 and swinging the fan 11. The pressure of the air against the fan causes it to turn slightly about its axis 32, so that the stroke of the fan directs the air towards the occupant of the chair. Upon the return movement of the chair the spring 41 takes up the slack of the rope 40 and causes the sheave 22 to reverse its rotation and thus impart a return swing to the fan 11, while also again varying its angular position as above 100 explained.

In connection with the ball joint construction 25, it should be noted that this permits the fan to be swung to different fixed positions so that the occupant of the 105 chair may be more or less in the path of the air current from the fan. Thus, if the fan is swung to an inward position the air current will be directed more nearly over the occupant of the chair, while if swung to 110 an outward position the air current is more in front of the occupant of the chair. In this way the air current can be varied to suit the user.

While in the present construction the fan 115 support is pivoted eccentric with respect to the ball joint 25, to cause an angular change in position of the fan, while oscillating, it is to be understood that this is merely one construction as obviously satisfactory results might be obtained by directly connecting the fan support to the ball joint or by variously associating these parts.

Although only a single form is shown in which this invention may be embodied, it is 125 to be understood that the invention is not limited to any specific construction, but might be applied in various forms without departing from the spirit of the invention or the scope of the appended claims.

Having thus described my invention, I claim:

1. The combination with a rocker member, means carried by said member for supporting a fan, means actuated by the rocking of said member for causing said fan to oscillate, and means for automatically varying the angular position of said fan while oscillating.
- 10 2. The combination with a rocker member, means carried by said member for supporting a fan, means actuated by the rocking of said member for causing said fan to oscillate, and means for automatically varying the angular position of said fan at one portion of each working stroke.
- 15 3. The combination with a rocker member, universal joint means carried by said member for supporting a fan, means actu-
- ated by the rocking of said member for 20 causing said fan to oscillate, and means for automatically varying the angular position of said fan while oscillating.
4. The combination with a rocker member, an oscillatory support carried by said member, means actuated by said member for actuating said support, a fan, and means including a universal joint for attaching said fan to said support, whereby the working position of said fan can be varied at 25 30 will and its angular position varied automatically at the beginning of each oscillation.

Signed at Philadelphia, county of Philadelphia, State of Pennsylvania, this 11th 35 day of September, 1922.

JOHN C. R. MARCH.
